UNITED STATES PATENT OFFICE.

FREDRIK ROSING BULL, OF CHRISTIANIA, NORWAY.

SAVING-CLOCK.

1,337,539.

Specification of Letters Patent. Patented Apr. 20, 1920.

Application filed June 28, 1917. Serial No. 177,458.

To all whom it may concern:

Be it known that I, FREDRIK ROSING BULL, citizen of Norway, and resident of Christian Augusts gate 13, in the city of Christiania and State of Norway, have invented certain new and useful Improvements in Saving-Clocks, of which the following is a specification.

So-called saving or economizing clocks have been in use for several years for the purpose of cashing savings, life-insurance premiums or the like. The principle consists in this that a certain coin must be inserted into the clock in order to keep the latter going. According to a previous construction the balance of the clock is caused to stop, if the coin is not inserted regularly.

According to my present invention the stopping and releasing device is placed in connection with the wind-up of the clock so as to allow only a certain number of revolutions to be effected between each time the coin is inserted. The device is in other respects quite independent of the clock and is attached at the inside of the box or casing inclosing the clock and the money-box, so that the device may be easily shifted, if it is desired to vary the amount to be cashed by the clock.

The invention is illustrated in the accompanying drawing, in which:

Figure 1 is a rear side view of an ordinary alarm-clock provided with the saving-device.

Fig. 2 is a detail view of the device showing the principal parts of the same seen from a side opposite to that of Fig. 1 and in a somewhat modified construction and on a larger scale.

Fig. 3 shows a modification of the saving device; Fig. 4 shows the disk supporting frame from the side opposite to that in Fig. 3.

—1— is the clock, —2— its inclosing casing, —3— the space for receiving the money-box (not shown), —4— the wind-up shaft end of the clock, —5— a rear plate mounted upon the clock or casing, and —6— a frame plate forming the supporting member of the saving device. The plate —6— supports pivotally two round disks, —7, 8—, each of which has on its circumference notch —9, 10—, respectively and also a gear wheel —11, 12— respectively intermeshing with each other. —13— is a pawl arm pivotally attached at —16— to the plate —6—

and provided with two pawls —14, 15— adapted to engage the said notches —9, 10— respectively. The number of teeth of the gear wheels —11, 12— is so arranged that the wheels, only after a definite number of revolutions of the wind-up shaft —4— or wheel —12—, will obtain such a position in relation to the wheel —11—, that the pawls —14, 15— are able to engage their respective notches —9— and —10— simultaneously and thereby to bar the rotation of the wheels, consequently also of the shaft —4—.

According to Fig. 2 of the drawings the teeth numbers of the wheels —12— and —11— are —23— and —24— respectively. Consequently the notches —10, 9— will obtain the same relative position only each time the wheel —12— has made 24 revolutions.

The disk —7— has a recess —17— forming a rest for the coin —18— to be inserted.

As soon as the pawls engage their notches, the parts are positioned as shown in the drawing. If now a coin —18— is inserted, it is received in the recess —17—, whereby it is just in contact with the pawl —14—. Since the notch —10— is somewhat larger than the width of the pawl —15—, the disk —8— can be rotated through a small angle. During such rotation the coin —18— operates the pawl —14— lifting the pawl arm —13— thereby disengaging the pawls —14, 15— from their notches —9, 10—, so that the disks may now be further rotated. After a half revolution of the disk —7—, the coin —18— falls down from the recess —17— into the money-box, and the shaft —4— can be rotated the definite number of revolutions (in the present example 24) before such rotation is stopped by the pawl, whereafter a new coin must be inserted again.

Instead of projecting the shaft —4— through the disk —8—, the latter may be simply provided with a square hole —4'—, through which the clock winding-key must be inserted in order to reach the said shaft.

In the modification shown in Figs. 3 and 4 the several parts corresponding to those shown in Figs. 1 and 2 are indicated by the same reference numerals, hence no special description of these parts will be necessary.

Instead of providing the coin-rest 17 on one of the disks as shown in Fig. 2, according to Fig. 3 the coin-rest 17' is here ar-

ranged upon the pawl arm —13—, the latter being in addition provided with a stop —19—. The coin —18— falls down between the arm —13— and a flat spring —20— attached to the inside of the casing —2—. The coin is held in the position shown in Fig. 3, thus forming a transmitting member between a push button —21— and the pawl arm —13—, disengaging the pawls 14, 15 when the button 21 is pushed in from outside. In other respects the operation is just the same as described with reference to Fig. 2.

Having now described my invention, what I claim as new and desire to secure by Letters Patent is:

1. Stopping and releasing device for saving-clocks comprising two rotatable notched disks, one being operatively connected with the wind-up of the clock, intermeshing gear wheels having a different number of teeth and attached each to one of said disks, a pawl arm, two pawls carried thereby, each pawl being arranged to engage the notch 25 in one of the said disks, when the latter as-

sume a definite mutually relative position, and a coin-rest so disposed that a coin supported thereby will operate as a medium for transmitting a releasing movement to the said pawl arm.

2. A stopping and releasing device, as specified in claim 1, having in combination with the coin-rest on the pawl arm and means for holding the coin in place a push-button operable from the outside and so arranged relative to the said pawl arm that upon being pushed inwardly, it moves, through the medium of the coin, the pawl arm so as to disengage the pawls.

3. A device as specified in claim 1, in which a spring is provided for holding the coin in operative position on the coin-rest formed on the pawl arm.

Signed at Christiania and State of Norway this 19th day of May A. D. 1917.

FREDRIK ROSING BULL.
